US0D1112672S

(12) **United States Design Patent** (10) Patent No.: **US D1,112,672 S**
(45) Date of Patent: ** Feb. 10, 2026

(54) **HUMIDIFIER**

(71) Applicant: **BEIANG AIR TECH LTD.**, Suzhou (CN)

(72) Inventors: **Dayou Zhang**, Suzhou (CN); **Hongyu Ran**, Suzhou (CN)

(73) Assignee: **SUZHOU BEIANG SMART TECHNOLOGY CO. LTD.**, Suzhou (CN)

(**) Term: **15 Years**

(21) Appl. No.: **29/866,408**

(22) Filed: **Sep. 11, 2022**

(30) **Foreign Application Priority Data**

Aug. 16, 2022 (CN) 202230533580.6

(51) **LOC (15) Cl.** **23-04**

(52) **U.S. Cl.**

USPC **D23/356**

CLAIM

The ornamental design for a humidifier, as shown and described.

DESCRIPTION

FIG. 1 is a front view of a humidifier showing our new design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines and the areas within them in all figures depict portions of the humidifier that form no part of the claimed design.

1 Claim, 7 Drawing Sheets
